CLAIM

The ornamental design for a stackable hair roller holder, as shown and described.

DESCRIPTION

FIG. 1 is a front and right side perspective view of a stackable hair roller holder showing my new design;

FIG. 2 is a top plan view thereof;

FIG. 3 is a front elevational view thereof;

FIG. 4 is a right elevational view thereof, with the left side elevational view being a mirror image thereof;

FIG. 5 is a rear elevational view thereof; and,

FIG. 6 is a bottom plan view of the stackable hair roller holder of FIG. 1.

The broken line showing of the cord is for illustrative purposes only and forms no part of the claimed design.
